UNITED STATES PATENT OFFICE.

KARL H. WOLLMANN, OF UNIONVILLE, CONNECTICUT.

TOOL-HANDLE.

1,070,221.

Specification of Letters Patent. Patented Aug. 12, 1913.

Application filed March 19, 1913. Serial No. 755,887.

To all whom it may concern:

Be it known that I, KARL H. WOLLMANN, a citizen of the United States, residing at Unionville, in the county of Hartford and State of Connecticut, have invented certain new and useful Improvements in Tool-Handles, of which the following is a specification.

This invention relates to tool handles, the object of the invention being to provide an article of this character which is simple in construction, susceptible of ready and inexpensive manufacture and which will securely yet detachably hold a tool.

In the drawings accompanying and forming part of the present specification I have shown in detail one of the several forms of embodiment of the invention, which to enable those skilled in the art to practice the same will be fully set forth in the following description. I do not limit myself to this disclosure; I may depart therefrom in several respects within the scope of the invention defined by the claims following said description.

Referring to said drawings: Figure 1 is a side elevation of a tool handle involving my invention, a part of a tool being shown. Fig. 2 is a longitudinal sectional view of said handle. Fig. 3 is a view corresponding to Fig. 2 and shows in elevation a tool connected with the handle. Fig. 4 is a longitudinal section, the section being in a plane at right angles to those of Figs. 2 and 3. Figs. 5 and 6 are transverse sections on the lines 5-5 and 6-6 respectively of Fig. 2.

Like characters refer to like parts throughout the several figures of the drawings.

A handle comprising my invention can be employed with advantage in connection with tools of various kinds, although it is of peculiar utility when used in conjunction with a file. Said handle is preferably provided with two sets of jaws which ordinarily are of such character as to positively and effectually prevent, when in engagement with the tool, movement of the latter, relatively to the handle in all directions. These two sets of jaws preferably also yieldingly engage the tool, one set of jaws being adapted to apply a greater pressure upon the tool, than the other. The best results are obtained by forming the jaws upon the forward terminals of the legs or branches of springs, said legs or branches moving the

jaws of the respective sets toward each other.

With the foregoing general description I will now refer more in detail to the specific form of the invention represented in said drawings.

The handle illustrated is denoted in a general way by 2 and comprises a body as 3 and a cap as 4 fitting the outer end of said body 3. The connection between the hollow body or tube 3 and cap may be of any suitable nature; for instance the cap may be held in place by a driving fit. As already intimated any kind of tool can be held by the handle 2, a file 5 being represented as thus held in Figs. 1 and 3 of the drawings, the forward end wall of the hollow body or tube 3 having an elongated slot 6 for the passage of the tang or shank of said file into said tube 3, where it can be engaged by the two sets of jaws to which brief allusion has been made.

The front jaws are denoted by 7 and 8, while the rear jaws are denoted by 9 and 10. Within the handle 2 are the opposite springs 11 and 12, each spring being doubled or bent upon itself to present an outer long branch and an inner short branch, the respective branches of the pairs being of approximately the same length. The jaw 9 is formed upon one short branch, while the mating jaw 10 is formed upon the other short branch, while the jaw 7 is formed on one long branch, the complementary jaw 8 being formed upon the other long branch. While the resiliency of the longer branches of the two holding springs may under some circumstances be sufficient to move the jaws 7 and 8 toward each other, this particular action is increased by having said long branches engage the inner wall of the tube or body 3 of the handle, said longer branches being bowed outward which not only provides for such engagement but also insures a rocking motion of said longer branches as the jaws 7 and 8 are opened and closed. The fact that the longer branches of the springs engage the relatively stationary bearing surface also augments the holding effect of the jaws 9 and 10 upon the tool, the holding effect being further increased at the rear, by reason of the fact that the inner branches of the springs are shorter than the outer branches. The two springs 11 and 12 are arranged opposite each other and I prefer to provide means for preventing relative

2
lateral movement thereof, and this means may be of any suitable character, the clip 13 within the body or tube 3 being shown for this purpose and embracing or straddling 5 the two springs at the junction of their respective branches.

Both sets of jaws are channeled by reason of which not only endwise movement of the tool 5 with respect to the handle 2 is prevented when said tool is engaged by said jaws, but relative lateral movement of the tool and handle is also precluded. The channeling of the two sets of jaws can be secured in any desirable manner, for instance by making the forward jaws 7 and 8 segmental form in cross section and by making the rear jaws 9 and 10 angular in cross section. (In Fig. 2 the jaws 7 and 8 and 9 and 10 are closed and in contact (see also Figs. 5 and 6), this relation being maintained by the branches of the two springs. The tang or shank of the tool 5 will be inserted through the slot 6 and first into the space between the jaws 7 and 8, said jaws 25 being spread or separated as the shank is moved rearward, the same operation being repeated with the jaws 9 and 10. In Fig. 3 the tool 5 is shown operatively connected with the handle 2, the two sets of jaws obtaining such a firm purchase upon the tang or shank of the file as to prevent absolutely relative longitudinal movement of the file and handle when the file is in use. Owing 30 also to the construction of the jaws, the file cannot move laterally at such time.

What I claim is:

1. A hollow tool handle provided with a

pair of interior opposite springs, each doubled on itself to present long and short branches, the short branches being located 40 between the long branches and normally bearing against each other and the long branches bearing against the interior wall of the handle, the free portions of the two sets of branches being adapted to detachably 45 engage a tool.

2. A hollow tool handle provided with two interior tool holding springs doubled on themselves to present long and short branches, the short branches being between 50 the long branches and each branch having a jaw, and a clip embracing the springs where their respective branches join.

3. A hollow tool handle provided with a plurality of springs doubled on themselves 55 to present long and short branches, said springs being opposite each other, the short branches being between the long branches, each pair of branches having jaws channeled on their opposite faces.

4. A hollow tool handle provided with two separate interior opposite tool holding springs doubled on themselves to present long and short branches, the short branches being between the long branches and each 65 branch having a jaw, and means for positively preventing relative lateral motion of the springs.

In testimony whereof I affix my signature in presence of two witnesses.

KARL H. WOLLMANN.
